UNITED STATES PATENT OFFICE.

HERMON S. ADAMS AND BYRON FAY, OF CLEVELAND, OHIO.

DESIGN FOR A MUCILAGE-BOTTLE.

Specification forming part of Design No. 6,116, dated September 3, 1872.

Specification describing a Design for Mucilage-Bottles, invented by HERMON S. ADAMS and BYRON FAY, of Cleveland, in the county of Cuyahoga and State of Ohio.

The nature of our design is fully represented in the accompanying drawing, to which reference is made.

A represents the body of the bottle, the sides of which are straight and perpendicular, and having a depression or panel, B, around the central part, in which depression are blown in the glass the words "Government Mucilage."

This constitutes the label on the bottle, and is to have no other label attached. The top of the bottle is crowning, and from the center arises the neck C.

What we claim as our invention is—

The design for a mucilage-bottle, substantially as above described and shown.

HERMON S. ADAMS.
BYRON FAY.
